US0D1100187S

(12) **United States Design Patent** (10) **Patent No.:** **US D1,100,187 S**
(45) **Date of Patent:** **** Oct. 28, 2025**

(54) **MEDICAL INJECTOR**

(71) Applicant: **SHL Medical AG**, Zug (CH)

(72) Inventor: **Daniel Scott**, Deerfield Beach, FL (US)

(73) Assignee: **SHL MEDICAL AG**, Zug (CH)

(**) Term: **15 Years**

(21) Appl. No.: **29/956,429**

(22) Filed: **Aug. 7, 2024**

Related U.S. Application Data

(60) Division of application No. 29/904,203, filed on Oct. 2, 2023, now abandoned, which is a continuation of application No. 29/834,682, filed on Apr. 13, 2022, now abandoned.

(57) **CLAIM**

The ornamental design for a medical injector, as shown and described.

DESCRIPTION

FIG. 1 is a front and top perspective view of the medical injector;

FIG. 2 is left side and rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the drawings illustrate portions of the injection device that form no part of the claimed design.

1 Claim, 5 Drawing Sheets
